UNITED STATES PATENT OFFICE

120,281

DESIGN FOR A COMBINED DRAPED CUR- TAIN AND VALANCE

David Kaplan, Los Angeles, Calif., assignor to California Curtain Mfg. Co., Ltd., Los Angeles,
Calif., a corporation of California

Application March 7, 1939, Serial No. 83,396

Term of patent 3½ years

To all whom it may concern:

Be it known that I, David Kaplan, a citizen of the United States, residing at Los Angeles, in the county of Los Angeles and State of California, have invented a new, original, and ornamental Design for a combined Draped Curtain and Valance, of which the following is a specification, reference being had to the accompanying drawing, forming part thereof.

The figure of the drawing is a plan view of the combined draped curtain and valance, showing my design.

I claim:

The ornamental design for a combined draped curtain and valance, as shown.

DAVID KAPLAN.
